(57) **CLAIM**

The ornamental design for a speaker enclosure, as shown and described.

DESCRIPTION

FIG. 1 is a rear view of a speaker enclosure showing my new design;

FIG. 2 is top view thereof;

FIG. 3 is a right side view thereof in an angled position, the

left side view being a mirror image;

FIG. 4 is a right side view thereof in an upright position, the

left side view being a mirror image;

FIG. 5 is a perspective view thereof in an angled position; and,

FIG. 6 is a perspective view thereof in an upright position. The broken line showing on the drawing disclosure is for illustrative purposes only and forms no part of the claimed design.
